US00D755219S

(12) United States Design Patent
Kim

(10) Patent No.: US D755,219 S
(45) Date of Patent: * May 3, 2016

(54) DISPLAY SCREEN OR PORTION THEREOF
WITH GRAPHICAL USER INTERFACE

(71) Applicant: AliphCom, San Francisco, CA (US)

(72) Inventor: Hyang Sook Kim, Chicago, IL (US)

(73) Assignee: ALIPHCOM, San Francisco, CA (US)

() Term: 14 Years

(21) Appl. No.: 29/495,387

(22) Filed: Jun. 30, 2014

(51) LOC (10) Cl. 14-04

(52) U.S. Cl.

USPC D14/486

(58) Field of Classification Search

USPC D14/485-495; D18/24-33;

715/700-867, 961-978; D5/40;

D10/40-45; D19/133

CPC G06F 3/048-3/04897; H04M 1/2477;

H04M 1/27519-1/72561; H04N 1/00408;

A63F 13/53; A63F 2300/308
